UNITED STATES PATENT OFFICE.

NORBERTO GUTIERREZ, OF ST. LOUIS, MISSOURI.

ORCHESTRA SOUND CABINET.

Application filed February 26, 1921. Serial No. 448,192.

To all whom it may concern:

Be it known that I, NORBERTO GUTIERREZ, a citizen of the Republic of Mexico, residing in the city of St. Louis, and State of Missouri, have invented new and useful Improvements in Orchestra Sound Cabinets, of which the following is a specification, reference being had to the accompanying drawings.

10 This invention pertains to sound-cabinets for musical instruments. It is especially designed for adding resonance and mellow-ness to the tones of phonograph instruments located therein, and for eliminating any 15 harshness of sound that might otherwise exist. One instrument, or several synchronized phonographs may be housed within this cabinet, and played singly or in unison; or the cabinet may be built large enough 20 to house a regular orchestra of many pieces.

In the drawings:

Figure 1 is a side elevation of the preferred form of construction of the cabinet, a portion of the wall and top being broken 25 away to show the method of construction.

Figure 2 is a top plan view.

Figure 3 is a horizontal section on the line A—B in Figure 1;

Figure 4 is a detail showing how the panels are hinged to the posts and uprights;

Figure 5 is a vertical section through the structure, showing the laminated form of the outer walls.

The invention consists in building a cabinet 35 1, large enough in diameter and height to entirely enclose the phonographs or other instruments designed to be housed therein.

The preferred form of this cabinet is multi-sided, as shown in the drawings, with sides 40 for instance, corresponding to the number of phonographs to be located therein; but the cabinet may be made circular, or square or triangular, and of course may be of any ornamental design desired.

45 In building the cabinet multi-sided as shown, a suitable base 15 is provided, cut to the required peripheral form. Posts 2 are mounted at the corners of this base, and sills 3 at the tops of the posts. Panels 4 are 50 then hinged to the posts 2, thus affording an easy access to the interior of the cabinet.

Upon the dado so formed is mounted an upper tone chamber 5, likewise of panel formation. For this purpose uprights 6 are extended above the sills 3, and top sills 7 55 are mounted on these uprights. Between these uprights 6 are hinged, or otherwise mounted, double walled panels 8, embodying the outer walls 9 of laminated wood, or other suitable structure, and the inner sound 60 or resonance boards 10, which are made of spruce or other suitable material, and spaced from the outer walls 9, so as to leave the intervening tone wells 11. These tone wells 11 have sound openings 12 leading 65 thereinto through the sound boards 10. The cabinet is finally provided with a reverberating top 13 made also of laminated wood and constructed to enhance sound waves, and this top 13 is spaced from the 70 body of the cabinet by short bars 14.

It is obvious that the precise form of construction may be varied in many ways without departing from the spirit of my invention, and while I have herein pointed out 75 a particular form of construction, it is understood same may be varied in minor details, not departing from the spirit of my invention as defined in the appended claims.

I claim:

1. An orchestra sound cabinet comprising double wall panels, the walls being spaced apart to form tone wells, the outer walls being imperforate and the inner walls being provided with openings communicating with the interior of the cabinet, and means for supporting said panels to form the sides of the cabinet.

2. An orchestra sound cabinet provided with inner and outer walls forming tone wells, the inner walls being provided with openings communicating with the interior of the cabinet.

3. An orchestra sound cabinet comprising a base, a double wall superstructure on the base partitioned into tone wells and having apertures leading through the inner walls into the tone wells.

NORBERTO GUTIERREZ.
